UNITED STATES PATENT OFFICE.

WINFORD D. PICKARD, OF NORMAN, OKLAHOMA.

GLARE GUARD FOR WINDSHIELDS FOR AUTOMOBILES, ETC.

1,424,939.

Specification of Letters Patent. Patented Aug. 8, 1922.

Application filed April 25, 1921. Serial No. 464,177.

To all whom it may concern:

Be it known that I, WINFORD D. PICKARD, citizen of the United States, residing at Norman, in the county of Cleveland and State 5 of Oklahoma, have invented certain new and useful Improvements in Glare Guards for Windshields for Automobiles, Etc., of which the following is a specification.

This invention relates to improvements in 10 the type of devices termed generally guards for wind shields for vehicles of the motor-class, as for instance sedans, coupes, automobiles and the like, while it may be readily adapted for application or use upon any 15 make or type of car or machine by simply changing or accordingly accommodating the attaching-clamps.

The invention has for its object chiefly to 20 serve as a guard in connection with a wind-shield, to serve as a septum or baffle to intercept a glaring action due to light-rays striking the glass-member of the wind-shield, also to guard against the otherwise view-obstructing action of rain or water striking the 25 glass-shield during a rain or snow storm.

A further object is to greatly simplify 30 construction and lessen the number of parts and to facilitate and expedite the carrying out of the aforesaid purposes.

Other objects of the invention will be apparent from the following description of the 35 construction and arrangement of the invention.

The invention consists therefore of the 40 various instrumentalities and features of construction substantially as hereinafter more fully disclosed and defined by the appended claim.

The accompanying drawing illustrates the 45 preferred embodiment of my invention or one form thereof wherein it will be understood that various changes and modifications as relate to the detailed construction and arrangement of parts may be made without departing from the spirit or scope thereof as 50 covered by the claim, and in which drawing:—

Figure 1 is a fragmentary perspective view showing my invention or guard applied 55 to the general type of wind shield as commonly used upon auto-cars, automobiles, sedans, coupes or other motor machines, the guard being shown as when in active use or extended position.

Figure 1^a is a section taken on the line 55 1^a—1^a of Figure 1.

Figure 2 is a similar view as Figure 1, showing the device principally in dotted line position as for instance when folded up out of use. 60

Figures 3, 4, 5, 6, 7, 8, and 9, are sundry detail views of individual elements of my guard.

As characteristic features of my invention, I employ a frame 1 adapted to be arranged 65 just in front of the ordinary wind-shield and comprising a longitudinal member terminating in end-transverse members pivotally supported upon the front of the cab 2 of the car. This pivotal connection is effected 70 preferably by means of studs or pivots 3 projecting from the transverse end members of said frame 1 and received by or bearing in apertured projections or studs 3^a projecting from the car-cab. 75

Suitably secured to the car or its cab, upon the under side of its roof or top, is a longitudinal strip or base member 4, and to this member or strip and the frame 1 are connected toggle-like jointed members or links 80 5 and 6. Each link or member 5 is pivoted at one end, as at 5^a, to a U-shaped keeper 5^b connected by bolts 5^x to the strip or base member 4, the member 4 being positioned sufficiently back of the projecting or overhanging edge of the cab-top to provide for taking the attachment thereunder out of the way, as seen in dotted lines in Figure 2, as when not required for use. The link or member 5 has its opposite end pivoted as at 90 5^c to the link or member 6, at any one of a plurality of perforations 7 therein, providing for the adjustability of the attachment as requirements may call for according to the type of vehicle upon which it may be desired to use it. The link or member 6 is of substantially elongated U-shape in transverse section as shown, thus providing for effecting connection of the link or member 5 interiorly therewith so as to permit it to 100 fold thereinto, particularly as seen in Figure 5, as required in compactly folding the device for the purpose above indicated. The link or member 6 has its inner end pivoted as at 8^a to a stud 8 suitably connected to the 105 frame 1 as shown.

In Figures 6 and 7 are disclosed (on enlarged scale) the securing bolts 5^x and U-

shaped keepers 5^{bb} for connecting the links 5^b to the member 4.

The frame-work, the resultant of the aforesaid arrangement of elements, has suitably applied thereto a water-proof covering 10, completing the formation of the guard or protector, which covering is adapted to be stretched tightly in position upon said frame-work when said elements have been disposed in extended position, which, it is apparent, will serve as a protector or guard against a glaring action, or rain and snow reaching the wind-shield.

As previously stated the guard, as above described, is an accessory or auxiliary for wind-shields used upon the motor-type of vehicles and is adapted to provide against the embarrassment of a glaring action and as against obstruction to the view, otherwise, from rain or snow contacting with or beating upon the wind-shield during a rain or snow storm.

It is also observed that the device or guard, adapted to be disposed wholly out of

the way when not needed, as described, will 25 not be in the way of the use or functioning of the wind-shield.

I claim and desire to secure by Letters Patent of the United States:

A wind-shield for automobiles, comprising 30 a hood-equipped, foldable or collapsible and extensible frame, whose lateral or side-portions are each formed of a plurality of pivoted-together link-members, the upper ends of the uppermost link-members having pivotal connection with the automobile, at its top-forward edge, intermediate link-members being proximately U-shaped, the resultant channels formed thereby receiving and providing for pivoting therein of other 40 of the link-members, whose inner ends are pivotally connected to the lower ends of the uppermost link-members, said intermediate links being mutually adjustable with respect to each other for shortening and 45 lengthening the shield appliance.

In testimony whereof I affix my signature.

WINFORD D. PICKARD.
